UNITED STATES PATENT OFFICE

102,983

DESIGN FOR A TEXTILE FABRIC

Curt Erwin Forstmann, Montclair, N. J.

Application June 2, 1936, Serial No. 62,950

Term of patent 14 years

To all whom it may concern:

Be it known that I, Curt Erwin Forstmann, a citizen of the United States, residing at Montclair, in the county of Essex and State of New Jersey, have invented a new, original, and ornamental Design for Textile Fabric, of which the following is a specification, reference being had to the accompanying drawing, forming part thereof.

In the drawing, the sole figure of which is a plan view of a piece of the textile fabric embodying the design of the present invention, the cloth depicted is of a single color.

The design consists of a series of woolly herringbone stripes interspersed with roundish nubs of hard finished worsted of higher elevation than the herringbone stripes, the prominence of the herringbone being subordinated to the appearance of the nubs in the design motif.

I claim:

The ornamental design for a textile fabric as described and as shown.

CURT E. FORSTMANN.
